WOODWORKING MACHINE

Francis E. Montgomery, Des Moines, Iowa, assignor of forty-nine per cent to Lee K. Weil, Des Moines, Iowa

Application August 17, 1933, Serial No. 685,573

5 Claims. (Cl. 144—84)

The object of my invention is to provide a wood working machine which is simple and durable.

A further object of my invention is to provide a wood working machine having novel features of construction whereby parts thereof requiring accuracy can be inexpensively manufactured yet by the substitution of said elements for elements now generally used in a wood working machine, the desired accuracy can be obtained.

More particularly it is my object to provide a wood working machine in which a work table is made adjustable in parallel planes without the necessity of having accurately machined sliding guide-ways which have a tendency to clog up with dirt and wear to such an extent that accuracy, after considerable use, is destroyed.

A further object is to provide means for supporting a work table relative to a saw mandrel or the like by means of links or bell cranks arranged in parallel, and adjusting means for the table in the form of a screw threaded shaft for swinging one of the links.

Still a further object is to provide novel means for mounting a motor and counter-shaft so that motor and counter-shaft belts can be changed on the various pulleys in a facile manner, and adjustment of the counter-shaft belt can be effected as desired.

Still a further object is to provide a novel form of base plate for supporting work with relation to the mandrel, which base plate is carried by a slideable frame, the frame itself being movable by novel mechanism.

A further object is to provide stop and depth gauges for the base plate and a means for spring returning the base plate, with the tension of the spring equal, regardless of the position of the base plate from the mandrel, this being effected by a spring urged element which is adjustable relative to the base plate.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a wood working machine embodying my invention.

Figure 2 is a plan view on the line 2—2 of Figure 1, the work table of the machine being removed and its supporting ears being shown in section.

Figure 3 is a partial plan and partial sectional

view on the line 3—3 of Figure 1, showing a base plate for work adjusted to a different position.

Figure 4 is a sectional view on the line 4—4 of Figure 3.

Figure 5 is a vertical sectional view on the line 5—5 of Figure 1; and

Figure 6 is a view similar to a portion of Figure 5 showing a different adjustment of parts.

On the accompanying drawings, I have used the reference character A to indicate generally a main frame. The frame A has supporting legs 10 whereby it may be supported relative to a floor surface or the like 12.

Cross bars 14 are mounted on the frame A and support bearings 16 in which a mandrel 18 is rotatably mounted. The mandrel 18 is adapted to have various tools mounted thereon, for instance a circular saw blade 20 and a lathe chuck 22. Other tools may be supported in a manner well known to those familiar with wood working machines.

For driving the mandrel 18, I provide a motor 24 mounted on a base plate 26. The base plate 26 is hinged at 28 to a motor and counter-shaft support 30. The support 30 is hinged at 32 to the main frame A.

A counter-shaft 34 is belted to the motor by a motor belt 36 and to the mandrel 18 by a counter-shaft belt 38.

The support 30 and the motor 26 and counter-shaft 34 carried thereby are counterbalanced by a spring 40. The position of the support 30 can be maintained by means of a bolt and wing nut 42 coacting with a slotted link 44 having its lower end pivoted to the support 30 and with a stationary bracket 46 extending from the frame A.

In connection with the saw blade 20, I provide a work table 48 which can be vertically adjusted yet maintained in positions at right angles to the saw blade by a supporting arrangement which will now be described. Supporting ears 50 depend from the lower surface of the work table 48 and links 52 have their upper ends pivoted thereto. The lower ends of the links are secured to shafts 54 oscillatable in the cross bars 14.

The shafts 54 are connected for simultaneous oscillation by depending arms 56 connected together by a link 58. The shafts 54 may be oscillated and the position of the work table 48 thereby changed by means of a crank 60. The crank 60 is secured to a rod 62 which is threaded into a yoke 64 connected with one of the arms 56. The rod 62 is rotatably but non-slidably extended through a side bar of the frame A.

In association with the mandrel 18, or more par-

ticularly the tool 22 thereon, I provide a base plate 64. It may be in the form of a plank or the like secured to a pair of arms 66. The arms 66 in turn are secured to base plate rods 68 which extend slidably through a cross bar 70 of the frame A. The frame A also has a cross bar 72 which has openings 74 for the base plate rods 68 to enter when the base plate is adjusted to its innermost position.

10 A slideable frame B is provided consisting of inner rods 76, outer rods 78 and cross bars 80. These are all assembled in rigid position relative to each other. The rods 76 extend through both the cross bars 70 and 72 while the rods 78 extend 15 through the cross bar 70 only. The base plate rods 68 are slideable through the cross bars 80 of the slideable frame B.

The base plate 64 is adjustably connected to the slideable frame B by means of a rod 82 rotatably 20 and non-slideably associated with the base plate and screw threaded relative to the right hand cross bar 80, on the drawings. A crank 84 is provided for rotating the rod 82.

A stop collar 86 is secured to one of the inner rods 76 to limit its movement toward the right. 25 A gauge collar 88 is adjustable along the other inner rod 76. A set screw 90 is provided for one of the base plate rods 68. The purpose of these will hereinafter be described.

30 Slidably mounted on one of the inner rods 76 is a spring urged element 92. It is of U shape, having one of its arms slideable on the rod 76 yet capable of being locked relative thereto by a set screw 94.

35 A spring 96 surrounds the rod 76 and is interposed between the cross member 70 and one arm of the spring urged element 92. The other arm of the spring urged element engages the opposite side of the cross bar 70.

40 A chain 97 is connected with the spring urged element 92 and extends over a pulley 98 and then to a foot pedal 100. The foot pedal 100 is pivoted at 102 and has a yoke 104 to selectively receive any link of the chain 97.

45 When it is desired to adjust the height of the work table 48, the crank 60 can be rotated in the proper direction for swinging the shafts 54 to positions as shown in Figure 5, one in solid lines and the other in dotted lines. It will be noted that 50 triple pulleys are provided for the motor belt 36. By swinging the motor base 26 to the dotted position of Figure 6, the motor shaft approaches the counter-shaft 34 so that this belt can be slipped from one pulley to the other for changing the 55 relative speeds between the shafts. The motor then returns the base to the full line position in which position the belt is taut.

60 Double pulleys are provided for the counter-shaft belt 38. This belt can be loosened by raising the support 30 to the position of Figure 5 so that it can be slipped from one to the other. To raise the support, the bolt 42 is first loosened whereupon the support, counterbalanced by the spring 40 can be raised with very little effort. 65 After the belt is placed upon the proper pulleys, the link 44 can be slid downwardly and the bolt 42 re-tightened.

70 With the set screw 90 and the gauge collar 88 loose, but the set screw 94 of the spring urged element 92 tightened, work can be placed against the base plate 64 and pulled toward the tool on the mandrel 18 so that the tool will operate on the work. This pulling is accomplished by depressing the foot pedal 100 against the action of the spring 75 96. Thus pieces of work can be quickly bored

when augers or bits are used or routed when routing bits are used.

To compensate for a thicker piece of work, the set screw 94 can be loosened and the frame B adjusted further to the right and then the set 5 screw 94 re-tightened or some adjustment can be had by rotating the crank 84. Where a slow speed of feed is desired, the crank 84 can be rotated without using the pedal 100.

In routing or boring work, it is sometimes desired 10 to rout or bore only to a desired depth. This depth can be regulated by tightening the collar 88 in the proper position so that when it engages the cross bar 70 of the main frame A it will stop feed movement of the base plate. In 15 routing work, it is sometimes desirable to use this gauge to the required depth and then hold the material at this depth while moving it over the base plate 64 to lengthen the routing hole into a routing slot. For this purpose the set screw 30 can be 20 tightened to retain the base plate 64 in a predetermined position relative to the frame A.

The lathe chuck 22 can be used in conjunction with a tail center 106, removably positioned on the base plate 64, and thus the device can be 25 used as a lathe with the crank 84 as an adjusting means for the tail center. A suitable tool rest, not shown, would then be used in connection with the machine, when used as a lathe.

A platform 108 may be mounted on the frame 30 A for supporting a planer, jig saw or other apparatus, the countershaft 34 being provided with a pulley 110 for driving such apparatus.

Some changes may be made in the construction 35 and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a wood working machine, a main frame, a mandrel rotatable thereon, a base plate for work to rest against, and means for mounting said base plate comprising a slideable frame supported on said main frame, said base plate being carried thereby, stop means for said slideable frame, a member slideable relative to said slideable frame and having a stop portion engageable with said main frame, a spring urging said member to assume its stopped position, means for locking said member to said slideable frame and a pedal for moving said member and thereby said slideable frame, when the two are locked together, against the action of said spring.

2. In a woodworking machine, a main frame, a second frame comprising rods slidably carried by said main frame and cross bars connected with said rods, a work rest carried by said second frame, a yoke on one of said rods and straddling a part of said main frame, a spring on said rod between said main frame and one arm of said yoke to constrain the other arm to engage said main frame, means for locking said yoke to said rod, and manually operable means for moving said yoke against the action of said spring.

3. In a woodworking machine, a main frame, a second frame comprising rods slidably carried by said main frame and cross bars connected with said rods, a yoke on one of said rods and straddling a part of said main frame, a spring on said rod between said main frame and one arm of said yoke to constrain the other arm to engage said main frame, means for locking said yoke to said rod, manually operable means for moving said

yoke against the action of said spring, a third frame slidable relative to said second frame, screw-threaded means for adjusting said third frame relative to said second frame, and a work rest carried by said third frame.

4. In a wood working machine, a main frame, a mandrel rotatable thereon, a base plate for work to rest against, and means for mounting said base plate comprising a slidable frame supported on said main frame, said base plate being carried thereby, a stop member for said slidable frame said stop member being movable relative to said slidable frame in the direction of its sliding movement, means for connecting said stop member in any desired position relative to said sliding frame, an abutment on said frame member for said stop member to normally engage, a spring urging said stop member toward said abutment, and a pedal operatively connected 20 with said stop member to move it and thereby

said slidable frame against the action of said spring.

5. In a wood working machine, a main frame, a mandrel rotatable thereon, a base plate for work to rest against, and means for mounting said base plate comprising a slidable frame supported on said main frame, said base plate being carried thereby, a stop member for said slidable frame, said stop member being movable relative to said slidable frame in the direction of its 10 sliding movement, means for connecting said stop member in any desired position relative to said sliding frame, an abutment on said frame member for said stop member to normally engage, a spring urging said stop member toward said 15 abutment and manually operable means for moving said stop member and thereby said slidable frame against the action of said spring.

FRANCIS E. MONTGOMERY. 20
